UNITED STATES PATENT OFFICE.

JACOB KAUFMANN, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

HEDDLE-FRAME.

1,168,308.

Specification of Letters Patent. Patented Jan. 18, 1916.

Application filed August 10, 1915. Serial No. 44,683.

To all whom it may concern:

Be it known that I, JACOB KAUFMANN, a citizen of the United States, residing at Philadelphia, in the county of Philadelphia 5 and State of Pennsylvania, have invented certain new and useful Improvements in Heddle-Frames, of which the following is a specification.

My invention relates to heddle frames and 10 it has particular relation to improved means for supporting the heddle bars intermediate their ends.

The principal object of my invention is to provide improved means for supporting the 15 heddle bars intermediate their ends which will be simple, durable, and efficient and which will permit the heddle bars to be readily assembled and detached from the frame.

My invention contemplates a device for 20 the aforesaid purpose which will more effectively prevent sidewise displacement and distortion of the heddle bars in the frame which has heretofore been the cause of much damage.

25 My invention further contemplates a form of device which, while effectively reducing wear upon the heddle bars at the place of support, will not of itself be the means of fouling with adjacent frames in the loom 30 when the same are rapidly reciprocated with respect to each other.

The nature and characteristic features of 35 my invention will be more readily understood from the following description taken in connection with the accompanying drawings forming part hereof, in which—

Figure 1 is an elevational view of a heddle frame provided with means embodying the main features of my present invention; Fig. 40 2 is an enlarged fragmentary detail view, partly in elevation and partly in section, of a portion of the structure shown in Fig. 1 illustrating the parts constituting the novel elements of my invention; Fig. 3 is a transverse vertical section taken on the line 3—3 45 of Fig. 2; and Fig. 4 is a perspective view illustrating the supporting link detached.

Referring to the drawings, the heddle frame there shown is of a common and well 50 known type comprising the top and bottom bars 5 usually made of wood and connected at their ends by metallic straps or bars 6. Mounted in and supported by the end bars 6 are the heddle supporting bars 7 upon which

the heddles 8 are mounted in the usual or 55 any desired manner.

At the places where it is desired to support the heddle bars intermediate their ends, the inner portions of the top and bottom bars 5 are recessed as at 9, the recesses being 60 less deeply cut near their ends to provide seats 10 upon which rest the ears 11 provided at the ends of auxiliary supporting bars 12. The auxiliary supporting bars 12 are disposed within the recesses 9 and extend within said recesses in the same general direction as the top and bottom bars 5 a distance sufficient for the required amount of sidewise movement of the heddle bar supporting links hereinafter referred to. The 65 preferred manner of forming the bars 12 is to take a strip of metal of substantially 70 rectangular cross section and twist the end portions thereof to form the ears 11 above referred to. The ears 11 of the bars 12 are 75 apertured for the fastening screws 13 which pass therethrough and are secured in the bars 5.

The heddle bar supporting links 14, shown 80 in perspective in Fig. 4 of the drawings, are 85 slidably but non-rotatably mounted upon the auxiliary supporting bars 12 and comprise open-sided links formed of a strip of metal of rectangular cross section of sufficient width to provide an effective bearing 85 surface both upon the auxiliary supporting bar 12 and the heddle bar 7, the ends of this strip being bent over at one end as at 15 and at the other end as at 16 to form the link as clearly shown in said Fig. 4 of the 90 drawings. The longer axis in cross-section of the strip from which said link is formed is disposed parallel to the longitudinal extension of the frame.

It will be noted that the recess 9 in the 95 top or bottom bar 5 is of sufficient depth to allow the link 14 to freely move upon the auxiliary supporting bar 12 in a longitudinal direction but that the turned over end 15 snugly engages the bar 12 so as to prevent 100 torsional or swinging movement of the link 14 with respect to the frame and that the turned over end 16 likewise snugly engages the heddle bar 7 so as to prevent rotation or distortion of the same. It will also be 105 noted that by making the link 14 as above described there will be no tendency to wear or cut through the heddle bar 7 or the sup-

porting bar 12 at any particular point as occurs when links or rigid hooks of relatively smaller width are employed as has heretofore been the uniform practice; and 5 furthermore, it will be noted that the link 14 while much stronger than the supporting links heretofore used at the same time is of less thickness so as in itself to form no obstruction projecting beyond the faces of 10 the heddle frame proper which would tend to foul on the parts of adjoining heddle frames as the same are reciprocated with respect to each other in the loom. Furthermore, by mounting the supporting bars 12 15 in the recesses 9 there will be no interference by these bars with the ends of the heddles which are mounted upon the bars 7 as has heretofore been the case where slideable supporting hooks have been used.

20 Having thus described the nature and characteristic features of my invention what I claim as new and desire to secure by Letters Patent is:

1. In a heddle frame, means for supporting the heddle bars intermediate their ends comprising auxiliary supporting bars mounted in recesses in the top and bottom bars of the heddle frame, and links slidably and non-rotatably mounted on said auxiliary supporting bars, the heddle bars being non-rotatably mounted in said links, and said links being formed of a strip of flat metal having its longest axis in cross-section disposed parallel to the longitudinal extension of the frame. 25
2. In a heddle frame, means for supporting the heddle bars intermediate their ends comprising auxiliary supporting bars mounted in recesses in the top and bottom bars of the heddle frame, and links slidably and non-rotatably mounted on said auxiliary supporting bars, the heddle bars being non-rotatably mounted in said links, and said links being formed of a strip of flat metal having its longest axis in cross-section disposed parallel to the longitudinal extension of the frame. 30
3. In a heddle frame, means for supporting the heddle bars intermediate their ends comprising auxiliary supporting bars mounted in recesses in the top and bottom bars of the heddle frame, and links slidably and non-rotatably mounted on said auxiliary supporting bars, the heddle bars being non-rotatably mounted in said links, and said links being formed of a strip of flat metal having its longest axis in cross-section disposed parallel to the longitudinal extension of the frame. 35

comprising auxiliary supporting bars mounted in recesses in the top and bottom bars of the heddle frame, and open sided links slidably and non-rotatably mounted on said auxiliary supporting bars, the heddle bars being non-rotatably mounted in said links, and said links being formed of a strip of flat metal having its longest axis in cross-section disposed parallel to the longitudinal extension of the frame. 40

3. In a heddle frame, means for supporting the heddle bars intermediate their ends comprising auxiliary supporting bars mounted in the top and bottom bars of the heddle frame, and open sided links slidably and non-rotatably mounted on said auxiliary supporting bars, the heddle bars being non-rotatably mounted in said links, said links being formed of a strip of flat metal having its ends bent over. 50

4. In a heddle frame, means for supporting the heddle bars intermediate their ends comprising auxiliary supporting bars mounted in the top and bottom bars of the heddle frame, and open sided links slidably and non-rotatably mounted on said auxiliary supporting bars, the heddle bars being non-rotatably mounted in said links, said links being formed of a strip of flat metal having its ends bent over and having its longest axis in cross-section disposed parallel to the longitudinal extension of the frame. 65

In testimony whereof, I have hereunto signed my name.

JACOB KAUFMANN.
